Allen Allen
ATTORNEYS

UNITED STATES PATENT OFFICE.

CHARLES W. PETERSON, OF DETROIT, MICHIGAN.

LOUD SPEAKER.

Application filed December 30, 1925, Serial No. 78,288.

My invention relates to cone type loud speakers and more particularly to that species of cone type loud speaker in which the conical diaphragm is supported at the 5 edge so as to be free to move as a whole on its mounting with the lower vibrations, and so as to be given no particular period of inherent vibration at the edges, as would be the case were the diaphragm supported on 10 tongues or springs.

The objects of my present invention are confined to the easy and sightly mounting of a conical diaphragm in a frame, bound with an aperiodic substance or otherwise, 15 which mounting is safe and strong, and avoids defects of structure which are to be found in other similar devices.

I accomplish my objects by that certain construction and arrangement of parts to be 20 hereinafter more specifically pointed out and claimed.

In the drawing:—

Figure 1 is a front elevation of my device.

Figure 2 is an elevation with the dia- 25 phragm and its connections in section.

Figure 3 is a section of the snap retaining ring.

Figure 4 is a detail section taken on the line 4—4 of Figure 1.

Figure 5 is a detail section taken on the line 5—5 of Figure 1.

Figure 6 is a rear view of the washer and nut structure.

Figure 7 is a side elevation of the nut.

Figure 8 is an edgewise view of the parts 30 shown in Figure 6.

Figure 9 is a detail of the lower section of the conical diaphragm.

I have illustrated my device as being 40 mounted in structure having a base 1, with a pedestal 2, to which is secured a metal ring 3. The ring is lined with a piece of felt illustrated at 4, where the diaphragm will contact therewith. The cone diaphragm is 45 indicated at 1^a.

The ring is formed by a stamping that leaves several arms 6, which are brought to a center in a slightly conical shape, where is 50 mounted the casing 7 of an electromagnetic receiver, whose armature is indicated at 8, and is connected with a wire 9.

The end of the wire is threaded as indicated at 10, and in mounting the conical dia- 55 phragm 1^a in the main ring, it is first set in place, with the wire passing through a hole in the center of the cone. Washers 12 and

13 are set over the wire, and nuts 14 and 15 on the wire are turned to clamp the apex of the cone between the said washers. The tension of the connection of the receiver 60 armature with the cone can thus be readily adjusted when assembling, and a preliminary test given to get the tension correctly applied.

Ordinarily once set, the tension at this 65 point of connection is not changed, although it is practical to do so, and as will be seen the attachment of the diaphragm to the armature wire controls the pressure of the edge of the cone against the felt seat in the 70 mounting ring.

As shown the ring 3 is formed of a metal stamping and is curled over partially on the side away from the felt surfacing. The snap ring or split ring 14^a is arranged to fit 75 into the cavity in the ring 3, and when the diaphragm is in place this ring 14^a is set into the main ring at the top and worked in down the sides and at the bottom, since it is a split body, and can be easily contracted.

In order to spread the ring and hold it fast in place against jarring loose, and at the same time to prevent a person twisting the conical diaphragm around and thus running a chance of breaking off the armature 80 wire, I provide a structure which is detailed in a number of the views. This is my preferred mode of accomplishing my object.

A washer 20 is provided which is of decorative appearance and engages the outside 85 of the split ring, overlapping the edges at the slit portion, so as to conceal the line of separation. This washer has a tongue 21 which is arranged to serve as a retainer against revolution of a nut on the washer 95 screw as will be noted. A notch 22 at the lower end of the cone diaphragm is engaged by this screw with the result of preventing the diaphragm from being revolved. A nut 23 having a conical outer face, is held to the washer by a screw 24 which is the screw above referred to. The nut 23 has a notch whereby it engages over the tongue 21, thus permitting the screw to be turned down and the washer and nut 100 brought together without revolving the nut.

The operator arranges the washer and nut together on the screw, and drops the nut inside the split ring, at the dividing point between its ends, and arranges the diaphragm 110 so that its notch is engaged by the tongue on the washer. He then turns the screw which

draws the nut into the space between the two meeting ends of the split ring. This expands the ring, due to the tapered or conical face of the nut and thus holds the ring tightly in place in the cavity of the outer ring.

The tongue on the washer lies in the flange of the supported ring, thereby preventing it from being dropped too low to hide the joint.

10. The face of the split ring is covered with a felt surfacing 25 and the proportion of the parts is such that the conical diaphragm rests upon felt and does not contact with any metal, nor is it in engagement with the felt 15 of either ring except to the extent of resting against that of the outer ring, with the felt of the split ring gently touching its surface.

A possible modification would be to stitch the felt to the conical diaphragm itself, but 20 this I do not find so satisfactory, as it is my object to mount the diaphragm with its periphery floating, and free of solid engagement so far as possible. There are also a number of ways of clamping the split ring 25 in expanded position after it has been inserted.

Having thus described my invention, what I claim as new and desire to secure by Letters Patent, is:—

30. 1. In a cone diaphragm loud speaker, the combination of a supported ring, a cone diaphragm, a split ring located within the supported ring, and means concealing the split in the latter ring and held thereto, said 35 means engaging a notch in the cone diaphragm.

2. In a cone diaphragm loud speaker, the combination with a supported ring, a cone diaphragm held thereon, and having a central aperture for connection with a receiver armature, a receiver having an armature mounted in connection with the supported ring, and having a wire projecting therefrom, said wire threaded at its ends, and 40 nuts on the wire and movable to engage the cone at the inside and the outside, for adjusting the tension of said diaphragm, and means for retaining the diaphragm in the said supported ring.

50. 3. In a cone diaphragm loud speaker, the combination of a supported ring, a split ring, a diaphragm adapted to be held between said rings, and means engaging the split ring so as to conceal the split therein, said means being adapted to spread the ring at the point of split.

4. In a cone diaphragm loud speaker, the combination of a supported ring, a split ring, a diaphragm adapted to be held between said rings, and means engaging the split so as to conceal the split therein, said means being adapted to spread the ring at the point of split, said means formed as a washer, having

a screw therein, and a conical nut on the screw and pulled thereby into the space 65 between the ends of the ring.

5. In a cone diaphragm loud speaker, the combination of a supported ring, a split ring, a diaphragm adapted to be held between said rings, and means engaging the split ring so 70 as to conceal the split therein, said means being adapted to spread the ring at the point of split, and said means having a projection adapted to engage a notch in the cone to hold said cone against revolution. 75

6. In a cone diaphragm loud speaker, the combination of a supported ring, a split ring, a diaphragm adapted to be held between said rings, and means engaging the split ring to hold it in expanded position in the supported ring, said diaphragm having a notch therein, and said means having a member to enter said notch, thus holding the diaphragm against revolution. 80

7. In a cone diaphragm loud speaker, the combination of a supported ring, a member mounted thereon, between which member and the ring a conical diaphragm is supported, and means for holding said member in position on the supported ring, a notch 90 in said diaphragm, said means arranged to engage said notch and prevent the diaphragm from being rotated.

8. In a cone diaphragm loud speaker, the combination of a supported ring, a member mounted thereon, between which member and the ring a conical diaphragm is supported, means for holding said member in position on the supported ring, and an element in connection with the member and its holding means for retaining the diaphragm in position against rotation in the supported ring, said diaphragm being arranged to rest at its periphery between said rings, but free of being gripped thereby. 100

9. In a cone diaphragm loud speaker having an annular supporting member, a cone diaphragm, a split ring member engaging said supporting member, and adapted to secure the peripheral edge of said diaphragm between said ring and said supporting member, said cone diaphragm provided with means to prevent rotation thereof, and co-operating means disposed between said support and said ring adapted to interlock with said diaphragm rotation preventing means. 110

10. In a cone diaphragm loud speaker having an annular supporting member, a cone diaphragm, a split ring member engaging said supporting member, and adapted to secure the peripheral edge of said diaphragm between said ring and said supporting member, and a clamping member engaging said split ring. 115
